SUBMARINE SALVAGING SYSTEM

Pablo Vilar Florida, United States Navy

Application May 24, 1932. Serial No. 613,247

2 Claims. (Cl. 114—51)

(Granted under the act of March 3, 1883, as
amended April 30, 1928; 370 O. G. 757)

This invention relates to new and useful improvements in means provided for indicating the position of a submerged submarine, and to facilitate the raising of the submarine by a salvaging ship.

Generally, the device consists of a plurality of attaching units associated with the submarine and with which are adapted to be attached complementary units carried by the salvaging ship, means being provided whereby the units carried by the salvaging ship may be guided into engagement with the units carried by the submarine.

Furthermore, in each unit associated with the submarine are located a buoy attached to the unit by a length of cable, the buoy being adapted to be released from the submarine when it has submerged, so as to indicate to the operators of the salvaging ship the position of the sunken submarine.

An important object of this invention is to provide a mechanism of this character that is simple and efficient, and wherein the units associated with the submarine may be carried in compartments directly within the submarine, and this without affecting the general construction of the submarine, and without retarding its movement through the water.

With the above and other objects in view the invention consists in the construction, combination and arrangements of parts as will be described more fully hereinafter.

Reference is to be had to the accompanying drawings forming a part of this specification wherein like reference characters indicate corresponding parts throughout the several views, and in which

Fig. 1 is a side elevation of a conventional submarine in submerged condition, the same being disclosed as in the process of being raised by a salvaging ship, the said submarine and salvaging ship being equipped with structural elements provided in accordance with the present invention.

Fig. 2 is a detailed longitudinal sectional view of a pair of the inter-engaged units carried by the submarine and salvaging ship to facilitate the raising of the submarine.

Fig. 2a is a front elevation partly broken away of the inter-engaged units.

Fig. 3 is a side elevation thereof,

Fig. 4 is a fragmentary section through a compartment built in the deck of the submarine, within which is located certain structural elements in accordance with the present invention,

Fig. 5 is an enlarged fragmentary longitudinal section through the lower free end of the units

carried by the salvaging ship and adapted to be lowered into engagement with a complementary unit associated with the sunken submarine, the unit illustrated being equipped at its outer end with a cable guide, and

Fig. 6 is an end elevation of this unit.

Now having particular reference to the drawings, A designates generally a conventional type of submarine, the deck of which in the present instance is equipped with a plurality of compartments 5. Each compartment is provided with a hinged door 6 normally closed, and adapted to be released by means 7 operable from the interior of the submarine. Loosely pivotally mounted within each compartment 5 is an attaching unit designated generally by the reference character B. Each unit consists of a bar 8 having at its inner end an offset eye 9 to facilitate its pivotal attachment within the compartment 5. The outer end of the bar is constructed with a tapered head 10, the inner end of which is provided with an undercut channel 11 for a purpose presently to be described. Extending longitudinally through this head 10 and the bar 8 is a cable bore 12, through which is extended one end of a considerable length of cable 13, the end of the cable after passing through the bore of the unit being rigidly attached to the inside of the submarine compartment 5.

Attached to the opposite end of the cable 13 is a suitable buoy 14 normally located within the said compartment 5, and obviously when the submarine has become submerged and cannot arise, the doors of the compartments 5 are opened, whereupon the buoys 14 will move to the surface of the water and float thereon for indicating the position of the sunken submarine, as generally indicated in Fig. 1.

Provided for cooperation with the units B carried by the submarine A are a plurality of units 95 designated generally C that are carried by the salvaging ship D. These units consist of a bar 15 having at their inner end in each instance an offset eye 16 for attachment to a cable carried by the salvaging ship. The opposite end of each unit is equipped with a tapering mouth 17 split longitudinally at opposite sides in order that the mouth can expand when moving into engagement with the head 10 of the complementary unit B. Within the outer end of the mouth 17 of each unit, the same is formed with an inwardly projecting circular rib 18 for engagement within the channel 11 of the head 10 of the cooperating unit B, see Fig. 2. The bar 15 of each C is provided with a longitudinal cable bore in order that 110

the said cable 13, after it has been brought upon the salvaging ship D, can be passed therethrough to afford a guide means for the particular unit C during its lowering into engagement with the respective submarine associated unit B, see Fig. 1. The weight of the units C are such that when dropping downwardly through the water, they will automatically engage upon the heads of the units B and lock thereon, so that when the cables attached to the units C are raised, the submarine will also be raised.

In order to prevent the cables 13 from getting caught within the slots of the mouths 17 of the units C, the outer ends of the mouths may be and preferably are equipped in each instance with a soft metal cable guide 19 that will break apart upon the expansion of the particular mouth to allow it to engage over the respective head of the unit B.

20 In view of the foregoing description when considered in conjunction with the accompanying drawings, it will be apparent that I have provided a novel, simple and useful means for indicating the position of a sunken submarine, and 25 to also facilitate the raising of the submarine, and even though I have shown and described herein the invention as consisting of certain detailed structural elements, it is nevertheless to be understood that some changes may be made therein without affecting the spirit and scope of the 30 appended claims.

The invention described herein may be manufactured and used by or for the Government of the United States for governmental purposes 35 without the payment of any royalty thereon or therefor.

What I claim as new is:

1. In a submarine salvaging means, in combination, a unit carried by a submarine, a head at the outer end thereof, a unit carried by a salvaging ship, an expansible mouth at the outer end thereof for engagement over the head of the submarine unit, co-acting means carried by the head and the mouth to prevent their separation after engagement, means cooperating with the submarine unit for guiding the salvaging ship unit into engagement therewith, said last mentioned means including a cable attached to the submarine unit and a buoy secured to its outer end to carry the cable to the surface of the water, and a severable cable guide carried by the salvaging ship unit.

2. In a submarine salvaging means, in combination, a unit carried by a submarine, a head at the outer end thereof, a unit carried by a salvaging ship, an expansible mouth at the outer end thereof for engagement over the head of the submarine unit, co-acting means carried by the head and the mouth to prevent their separation after engagement, said means comprising a channel at the inner end of the head of the submarine unit and a rib within the mouth of the salvaging ship unit for engagement in said channel after the mouth has been disposed over the head, means cooperating with the submarine unit for guiding the salvaging ship unit into engagement therewith, and a severable cable guide mounted in the mouth of the salvaging ship unit.

PABLO VILAR FLORIDO.
